US0D1037690S

(12) **United States Design Patent** (10) **Patent No.:** **US D1,037,690 S**
(45) **Date of Patent:** **** Aug. 6, 2024**

(54) **FOLDING CHAIR**

(71) Applicant: **NINGBO TIANLI DAILY USE PRODUCTS CO., LTD.**, Yuyao (CN)

(72) Inventor: **Fangfang Wei**, Yuyao (CN)

(73) Assignee: **NINGBO TIANLI DAILY USE PRODUCTS CO., LTD.**

(**) Term: **15 Years**

(21) Appl. No.: **29/932,485**

(22) Filed: **Mar. 14, 2024**

(51) LOC (14) Cl. **06-01**

(52) U.S. Cl.

USPC **D6/368**

(58) **Field of Classification Search**

USPC D6/364-371, 375, 379, 380

CPC A47C 1/14; A47C 4/03; A47C 4/08

See application file for complete search history.

(57) **CLAIM**

The ornamental design for a folding chair, as shown and described.

DESCRIPTION

FIG. 1 is a front, right, top perspective view of a folding chair, showing my new design;

FIG. 2 is a rear, left, bottom perspective view thereof;

FIG. 3 is a front, right, bottom perspective view thereof;

FIG. 4 is a front elevational view thereof;

FIG. 5 is a rear elevational view thereof;

FIG. 6 is a left side view thereof;

FIG. 7 is a right side view thereof;

FIG. 8 is a top plan view thereof;

FIG. 9 is a bottom plan view thereof; and,

FIG. 10 is a front, right, top perspective view of the folding chair, indicating the usage environment.

The broken lines are for environmental purposes only and form no part of the claimed design.

1 Claim, 10 Drawing Sheets
